UNITED STATES PATENT OFFICE

2,457,576

AIRPLANE PROPELLER AND MEANS FOR
ADJUSTING SAME

John G. Littrell, San Antonio, Tex.

Application July 20, 1944, Serial No. 545,767

3 Claims. (Cl. 170—160.11)

1

The present invention relates to improvements in airplane propellers and means for adjusting same and more particularly relates to a mechanism incorporated in the propeller structure and rotating therewith, whereby the blades may be both angularly adjusted as to pitch and also moved in and out radially, to change the elongation of the blade from the propeller center of rotation.

An object of the invention is to accomplish the two purposes of pitch changing and radial elongation by the simply constructed, compact and efficiently operating mechanism that lends itself to inclusion within small compass in the hollow shaft of the propellers.

Another object of the invention is to provide a device for the above purposes which will be faithful in performance and so constructed and arranged as to avoid the possibility of binding or freezing of the parts.

With the foregoing and other objects in view, the invention will be more fully described hereinafter, and will be more particularly pointed out in the claims appended hereto.

In the drawings, in which the same reference characters indicate the same parts throughout the several views,

Figure 1 is a fragmentary longitudinal section taken through an improved propeller constructed in accordance with the present invention;

Figure 2 is a transverse section taken on the line 2—2 of Figure 1;

Figure 3 is a similar section taken on the line 3—3 in Figure 1, on an enlarged scale;

Figure 4 is a fragmentary longitudinal cross section of the propeller socket showing the inclined or spiral grooves;

Figure 5 is a cross section taken on an enlarged scale on the line 5—5 of Figure 1;

Figure 6 is a similar view taken on line 6—6 also in Figure 1; and

Figure 7 is a front elevation, taken on a small scale of a two-blade propeller with the outer position of the blades indicated in dotted lines.

Referring more particularly to the drawings, 10 designates a control shaft, concentric with and mounted within the tubular driving shaft 55 and having a ring gear 14 mounted within hub housing 11, of a conventional airplane propeller construction having tubular propeller receiving sockets 12 radiating therefrom. For purposes of illustration only, one such propeller receiving socket has been shown in the accompanying drawings, best seen in Figure 1; however it is understood that any desired number of such

2

sockets may be radially mounted about the hub housing 11. A propeller blade 13 is slidably and rotatably received over the receiving socket 12.

The shaft 10 drives a ring gear 14 with which mesh one or more pinions 15, one for each propeller blade. The pinion 15 is fastened on a screw shaft 16 mounted to rotate, but against endwise or axial movement, in a bearing 17. The thread of the shaft is indicated at 18, the same engaging with complementary threads upon a traveling nut 19. Made fast to the nut is a sleeve 20 having two or more radial keys 21 projecting outwardly and sliding in slotted guides 22 fixed by fastenings 23 to the inside wall of the tubular propeller socket 12.

The outer end of the sleeve 20 is slipped over a reduced neck 24 of a slidable cross head 25 and affixed thereon by fastenings 26. A companion slidable and rotatable cross head 27 is associated with the slidable cross head 25, there being ball bearings 28 between the two heads and a universal connection rod 29 passing axially through the two cross heads and into sockets 30, 33 and 34 of the cross heads; the rod 29 carrying nuts 31, 32 and 35 in such sockets. This construction permits the cross head 27 to rotate relatively to its companion cross head 25, but insures entrainment of both cross heads 25 and 27.

Spiral grooves 36 in the internal wall of the tubular propeller socket 12 receive keys 37 projecting from the outer cross head 27 to cause rotation of this outer cross head on the axial sliding of such cross head. A spindle 38 is received at its inner end into a socket 39 of the outer cross head 27 and a pin 40 secures the spindle to the cross head. A coil spring 41 is wound in a suitable number of convolutions around the spindle 38 having one end abutting against the outer cross head 27 and its outer end 40 engaging against a web 42 projecting inwardly from a connecting ring 43. Such ring is threaded, as indicated at 44, to mate with threads upon the reduced outer end of the tubular propeller socket 12. The web 42 is apertured at 45 to slidably receive the spindle 38 therethrough. The ring 43 carries an extension ring 46 outwardly of web 42 to envelop the reduced or stepped-down end 47 of the propeller blade 13. A bearing portion 48 of the blade outwardly of the reduced part 47 lies between this reduced end 47 and a groove 49 of the blade root. The groove 49 receives an inturned flange 50 of a tapered sleeve 51, movable with the blade 13 and enveloping and operable upon the outer portion of the tubular propeller

53 socket 12 to conceal, and exclude foreign matter

from, the joints made by the sleeve 43 and adjacent parts. A retaining ring 52 may be shrunk or otherwise fitted about the flange portion 50 of the sleeve 51. The sleeve preferably tapers inwardly to merge gradually with the external contour of the hollow propeller socket 12 in order to avoid any disturbance of the aerodynamic balance.

At its outer end the spindle 38 is received into a socket 53 of the propeller blade 13 in which it is secured as by a pin 54.

Referring more particularly to Figure 2, one form of drive for the ring gear 14 is shown in which the shaft 10 enters through an outer tubular shaft 55. This outer shaft 55 may be connected to the airplane engine for rotating the propeller as a whole. The inner shaft 10 may be connected to any adjusting mechanism, for instance to an electric motor and its reduction gear.

In operation, as indicated in Figure 7, the propeller blades 13 may be adjusted outwardly within the range of the dotted lines. Simultaneously with this adjustment, the blades 11 are also rotated angularly about their longitudinal axes to effect pitch changes. In order to accomplish this result, the control shaft 10 is turned the desired number of revolutions in a like manner rotating the ring gear 14 and the enmeshed pinion 15. The consequent rotation of the screw shaft 16 will cause the nut 19 to travel in or out on such screw shaft 16 in accordance with its direction of rotation. In moving out, the nut 19 will carry with it the sleeve 20 and the two cross heads 25 and 27. The outer cross head, by virtue of the groove 36 and key 37 construction, will be rotated as it moves outwardly to secure pitch change. The rotary motion of the outer cross head 27 is communicated through the spindle 38 and to the blade 13.

The coil spring 41 will be compressed incident to the outer movement of the cross heads and will act to expand inwardly and drive the cross heads inwardly when the power is removed from the shaft 10. Thus the parts are biased to an inner position.

The drawings show only one embodiment of the invention, which is best known to me at this time, but it will be understood that these drawings are only illustrative of a construction and one embodiment of the invention. It will be understood that the invention is susceptible of

embodiment in various other forms, all within the scope of the following claims.

What is claimed is:

- 5 1. In an airplane propeller, a hub, tubular propeller sockets radiating from said hub, a blade movable inwardly and outwardly of said hub with respect to said tubular propeller sockets and also adjustable angularly, substantially about the axis of the socket, a spindle, one end of which is affixed to said blade and located concentrically within said socket and the other end of which is affixed to a first cross head, a second cross head movable radially in said socket and fixedly coupled to said blade means to move said first cross head radially in said socket, and means between said cross heads and sockets for requiring said second cross head to rotate incident to its radial traverse.
- 10 2. An airplane propeller as claimed in claim 1 wherein a spring helix envelops the spindle which links the propeller blade with the cross head and biases same to inner position and is compressed by the outward movement of said cross head.
- 15 3. An airplane propeller as claimed in claim 1 wherein the means for rotating said second cross head comprises spiral grooves in said tubular propeller sockets for receiving and guiding keys carried by said second cross head.
